US00D804443S

(12) **United States Design Patent** (10) **Patent No.:** **US D804,443 S**
(45) **Date of Patent:** **** Dec. 5, 2017**

(54) **MOBILE TERMINAL**

(71) Applicant: **SAMSUNG ELECTRONICS CO., LTD.**, Suwon-si (KR)

(72) Inventors: **Byung-Jin Kang**, Seoul (KR); **Do-Hyung Lee**, Yongin-si (KR); **Kyu-Hong Kim**, Yongin-si (KR)

(73) Assignee: **SAMSUNG ELECTRONICS CO., LTD.**, Gyeonggi-Do (KR)

(**) Term: **15 Years**

(21) Appl. No.: **29/559,841**

(22) Filed: **Mar. 31, 2016**

(30) **Foreign Application Priority Data**

Oct. 2, 2015 (KR) 30-2015-0049862
Oct. 2, 2015 (KR) 30-2015-0049872

(57) **CLAIM**

The ornamental design for a mobile terminal, as shown and described.

DESCRIPTION

FIG. 1 is a perspective view of a mobile terminal showing our new design;

FIG. 2 is a front view of FIG. 1;

FIG. 3 is a rear view of FIG. 1;

FIG. 4 is a left-side view of FIG. 1;

FIG. 5 is a right-side view of FIG. 1;

FIG. 6 is a top plan view of FIG. 1;

FIG. 7 is a bottom plan view of FIG. 1;

FIG. 8 is another perspective view of FIG. 1 in a folded position;

FIG. 9 is a front view of FIG. 8;

FIG. 10 is a rear view of FIG. 8;

FIG. 11 is a left-side view of FIG. 8;

FIG. 12 is a right-side view of FIG. 8;

FIG. 13 is a top plan view of FIG. 8; and,

FIG. 14 is a bottom plan view of FIG. 8.

The broken lines illustrating portions of the mobile terminal form no part of the claimed design.
